DESIGN FOR A SHOE POLISHER OR SIMILAR ARTICLE

Ernest E. Baldwin, Spokane, Wash.

Application June 21, 1938, Serial No. 77,966

Term of patent 3½ years

To all whom it may concern:

Be it known that I, Ernest E. Baldwin, a citizen of the United States of America, residing at Spokane, in the county of Spokane and State of Washington, have invented a new, original, and ornamental Design for a Shoe Polisher or Similar Article, of which the following is a specification, reference being had to the accompanying drawing, forming part thereof.

Fig. 1 is a front perspective view of a shoe polisher or similar article showing my new design; and

Fig. 2 is a rear perspective view thereof.

I claim:

The ornamental design for a shoe polisher or similar article, as shown.

ERNEST E. BALDWIN,
